United States Patent Office

Des. 188,774
Patented Sept. 6, 1960

188,774

EXPOSURE METER

Yoshio Akioka and Yoshio Mishina, Tokyo, Japan, assignors to Seiko Denki Kogyo Kabushiki Kaisha, Tokyo, Japan

Filed Mar. 13, 1958, Ser. No. 50,012

Term of patent 14 years

(Cl. D61—1)

Fig. 1.

Fig. 5.

Fig. 2.

Fig. 6.

Fig. 3.

Fig. 4.

Fig. 1 is a top plan view of an exposure meter showing our new design;

Fig. 2 is a bottom plan view thereof;

Fig. 3 is a lower side elevational view thereof;

Fig. 4 is an upper side elevational view thereof;

Fig. 5 is a front elevational view thereof; and

Fig. 6 is a rear elevational view thereof.

We claim:

The ornamental design for an exposure meter, as shown.
